UNITED STATES PATENT OFFICE.

WILLIAM H. EBELHARE AND CLARENCE G. ARVIDSON, OF INDIANAPOLIS, INDIANA,
ASSIGNORS TO THE STENOTYPE COMPANY, OF INDIANAPOLIS, INDIANA.

TYPE-WRITING MACHINE.

1,252,890.

Specification of Letters Patent. Patented Jan. 8, 1918.

Application filed November 21, 1916. Serial No. 132,614.

To all whom it may concern:

Be it known that we, WILLIAM H. EBELHARE and CLARENCE G. ARVIDSON, citizens of the United States, and residents of Indianapolis, in the county of Marion and State of Indiana, have invented certain new and useful Improvements in Type-Writing Machines; and we do hereby declare the following to be a full, clear, and exact description of the invention, such as will enable others skilled in the art to which it app pertains to make and use the same.

This invention relates to improvements in typewriting machines, and more particularly to means for holding and receiving a paper strip such as employed with stenographic typewriting machines—the object of the invention being to equip a stenographic typewriting machine with means which shall serve as a magazine for a paper strip folded to form superposed layers and to receive the strip after the record has been printed thereon and permit the same to be deposited in superposed layers, whereby the printed strip shall be readily accessible for inspection.

A further object is to provide a stenographic typewriting machine with a paper receptacle which shall be compact and attached permanently to the frame of the machine, and which shall be collapsible so as to occupy but little space and be out of sight when the machine is not in use.

A further object is to provide a paper receptacle which shall normally occupy the bottom portion of the main frame of the machine and be out of the way of the operating mechanism.

With these and other objects in view, the invention consists in certain novel features of construction and combinations of parts as hereinafter set forth and pointed out in the claims.

In the accompanying drawings; Figure 1 is a view of the blank from which the fixed portion of the paper receptacle is made; Fig. 2 is a plan view of said fixed portion of the receptacle; Fig. 3 is a view of the end of the sliding or extensible member of the receptacle; Fig. 4 is a blank from which a portion of the sliding member is made; Fig. 5 is a

plan view of a portion of the sliding member made from the blank shown in Fig. 4; Fig. 6 is a plan view of the bottom plate of the sliding member; Fig. 7 is a plan view 55 of the completed sliding member; Fig. 8 is an enlarged view showing the machine frame in section and the paper receptacle in end elevation; Fig. 9 is a perspective view of the paper receptacle; 60 Fig. 10 is an enlarged fragmentary section view; Fig. 11 is a view of a stenographic typewriting machine, partly in section, showing the application of our improvement with the paper receptacle closed 65 or collapsed, and Fig. 12 is a similar view showing the receptacle extended; as when the machine is in use.

1 represents the frame of a stenographic typewriting machine provided interiorly 70 near its bottom with lugs 2, and the printing and paper feeding devices of the machine are indicated at 3 and 4 respectively.

Within the bottom portion of the frame 1, our improved extensible paper tray or receptacle is located and housed by said frame when the tray is in collapsed position.

The tray or receptacle comprises two members,—viz. a member 5 secured to the machine frame, and a member 6 having sliding 80 connection with the member 5 and adapted to be extended rearwardly from the machine when the latter is in use, as shown in Fig. 12.

In constructing the fixed member 5 of the tray, we may first provide a sheet metal 85 blank, (preferably aluminum,) having the shape shown in Fig. 1. This blank is bent on the lines 7, 7 to form the sides 8, 8 of the tray member 5; the side portions of the blank are bent on the lines 9, 9 whereby lateral 90 wings or plates 10, 10 are formed, and one end of the blank is bent upwardly on the line 11 to form an end flange 12 for said fixed tray member. The body portion of the tray member 5 is provided with a slot 13 95 for a purpose hereinafter explained, and the horizontal wings or plates 10 are provided with holes 14 for the passage of screws 15 for securing the tray member 5 to the lugs 2 in the lower portion of the frame 1,— 100 said screws also serving to secure rubber feet 16 to the machine frame.

The body portion of the extensible member 6 of the tray or receptacle is formed from the blank shown in Fig. 4. This blank is bent on the lines 17, 17 to form the sides 18 of said member 6. At one end, the blank is bent on the lines 19, 19, 20 to form inwardly projecting flanges 21, 21, 22 to which an end plate 23 is riveted, said end plate being provided with a finger hole 24. The extensible member 6 is provided on its bottom with a plate 25 which is securely riveted thereto and made of sufficient width to form flanges 26. The member 6 is movable between the sides 8 of the member 5. Lugs 27 are secured to the sides 8 of the fixed tray member so as to overlie the lateral flanges 26 of the movable tray member 6, and serve to guide the latter and prevent displacement or binding thereof. The inner end of the tray member 6 is made with a recess 28 to receive the end flange 12 of the tray member 5 when the former is telescoped into the latter. The tray member 6 is also provided near its outer end with lateral opening 29 to give ready access to the paper for removing the same.

The extensible or telescopic member 6 is provided on its bottom with a spring finger 30 which may have frictional engagement with the tray member 5 to prevent accidental displacement of the member 6, and when the latter is extended, this spring finger will enter the slot 13 in the member 5 and thus complete withdrawal of the member 6 will be prevented.

The rear end of the frame or casing 1 is made with an opening 31 to permit the tray member 6 to be extended as shown in Fig. 12, but when the parts of the tray are in collapsed position, as shown in Fig. 11, the opening 31 will be closed by the end plate 23 of the extensible tray member 6.

When the machine is in use and the paper tray or receptacle is extended as shown in Fig. 12, the paper strip in superposed folded layers 32 will be located in the portion of the receptacle which is under the machine frame, and the paper will pass from the pile 32 and after passing through the printing and feeding mechanism, will be deposited in folded layers in the extended tray member 6, as indicated at 33.

Our improvements permit the use of a folded paper strip and the accumulation of the printed record strip in superposed folds, so that it may be readily handled and inspected as occasion may require.

Various changes might be made in the details of construction of our invention without departing from the spirit thereof or limiting its scope and hence we do not wish to restrict ourselves to the precise details herein set forth.

Having fully described our invention what we claim as new and desire to secure by Letters-Patent, is:—

1. In a typewriting machine, the combination with a frame and printing and paper feeding mechanisms, of a paper receptacle supported by the lower portion of the frame, 70 said receptacle comprising a member disposed in the frame to receive a supply folded paper strip, and a member adapted to be disposed rearwardly of the frame and the printing and feeding mechanisms to receive 75 the printed strip in superposed folded layers.

2. The combination in a typewriting machine, of a paper receptacle comprising telescopic members, one of said members being secured to the frame and the other member 80 being movable beyond the frame.

3. The combination in a typewriting machine, of an extensible paper receptacle connected with the lower portion of the frame thereof and collapsible into said frame. 85

4. The combination in a typewriting machine of a paper receptacle comprising two members, means for fixing one of said members in the bottom of the frame of the machine, the other member being movable into 90 and out of the fixed member, and means for preventing accidental disconnection of one of said members from the other.

5. The combination with the frame of a typewriting machine, of a paper receptacle 95 comprising a tray member fixed in said frame, a slidable member movable in the fixed member and provided with lateral flanges at its bottom, lugs secured to the sides of the fixed member and disposed over 100 said flanges, and means for preventing accidental detachment of the movable member from the fixed member.

6. The combination with the frame of a typewriting machine, of a paper tray comprising two members, one of said members being secured in the bottom portion of the machine frame in position to receive a blank folded paper strip, and the other member being movably mounted and adapted 110 to be projected beyond the first mentioned member in position to receive the printed paper strip as it comes from the printing means of the machine.

7. A paper tray for typewriting machines, 115 comprising a member provided with means for securing the same to a typewriting machine and adapted to receive a supply sheet in superimposed layers, and a member movably connected with the fixed member of the tray 120 and adaptable to receive the printed sheet in superimposed layers.

8. A paper tray comprising a member having wings for attachment to the frame of a typewriting machine, and a movable 125 member disposed within the first-mentioned

member, means for guiding the movements of the movable member, and a spring tongue carried by the movable member and coöperable with the bottom of the first-mentioned member to control the movements of said movable member.

In testimony whereof we have signed this

specification in the presence of two subscribing witnesses.
